Patented June 12, 1900.

E. T. GILBERT.

GUY CLAMPING PLATE.

(Application filed Apr. 24, 1900.)

UNITED STATES PATENT OFFICE.

EDWARD T. GILBERT, OF DETROIT, MICHIGAN.

DESIGN FOR A GUY CLAMPING-PLATE.

SPECIFICATION forming part of Design No. 32,827, dated June 12, 1900.

Application filed April 24, 1900. Serial No. 14,192. Term of patent 7 years.

To all whom it may concern:

Be it known that I, EDWARD T. GILBERT, a citizen of the United States, residing at Detroit, county of Wayne, State of Michigan, have invented and produced a new and original Design for a Guy Clamping-Plate, of which the following is a specification, reference being had to the accompanying drawings, which form a part of this specification.

10 In the drawings, Figure 1 is a plan view of a guy clamping-plate, showing my new design. Fig. 2 is a vertical section on the line 2 2, Fig. 1. Fig. 3 is a vertical section on the line 3 3, Fig. 1, Figs. 2 and 3 being arranged in the same plane. Fig. 4 is a view in section on the line 4 4, Fig. 1.

As shown in the drawings, a represents a clamping-plate.

15 The leading or material features of my design consist of a plate grooved longitudinally on each side thereof, as indicated at a^1 and a^2 , each of the grooves being provided with corrugations formed of a series of depressions a^3

and a series of raised portions or ribs a^4 , the depressions and raised portions of said grooves on opposite sides of the plate alternating, the depressions of one groove being located opposite the raised portions of the other groove. On the outside of each groove is a marginal rib, rising above the corresponding groove, as 25 shown. Between said grooves is a plane surface, rising above the grooves. The plate is provided with bolt-orifices in the raised plane surface intermediate the grooves, (indicated at a^5 .)

30 Having described my invention, what I claim as new, and desire to secure by Letters Patent, is—

35 The design for a clamping-plate, substantially as herein shown and described.

40 In testimony whereof I sign this specification in the presence of two witnesses.

EDWARD T. GILBERT.

Witnesses:

N. S. WRIGHT,
O. B. BAENZEGER.
